UNITED STATES PATENT OFFICE.

ERNST LEDER, OF BERLIN, GERMANY.

CALCULATING-MACHINE.

No. 902,498.

Specification of Letters Patent.

Patented Oct. 27, 1908.

Application filed January 18, 1908. Serial No. 411,380.

To all whom it may concern:

Be it known that I, ERNST LEDER, a subject of the Emperor of Germany, and a resident of Berlin, Germany, have invented a 5 new and Improved Calculating-Machine, of which the following is a full, clear, and exact description.

This invention relates to calculating machines, and more particularly devices of this 10 kind depending upon logarithmic principles for their operation.

An object of the invention is to provide a simple and efficient machine of the class described, by means of which the logarithms of 15 numbers can be ascertained and by means of which logarithmic calculations can be effected.

A further object of the invention is to provide a calculating machine by means of which ordinary arithmetical calculations can 20 be made rapidly and accurately by the employment of logarithmic principles.

A still further object of the invention is to provide a calculating machine by means of which numbers can be ascertained when the 25 respective logarithms of the numbers are known, and which has a logarithmic scale so sub-divided and graduated that the logarithms of numbers from zero to ten thousand, and numbers from zero to ten thousand 30 corresponding to known logarithms, can be ascertained therewith.

The invention consists in the construction and combination of parts to be more fully described hereinafter and particularly set 35 forth in the claims.

Reference is to be had to the accompanying drawings forming a part of this specification, in which similar characters of reference 40 indicate corresponding parts in all the views, and in which

Figure 1 is a longitudinal section of the calculating machine on the line 1—1 of Fig. 2; Fig. 2 is a plan view of the machine showing a part of the cover broken away; Fig. 3 is 45 an enlarged plan view of a detail of the mechanism; Fig. 4 is a plan view of a portion of the logarithmic scale employed, showing parts broken away; Fig. 5 is an enlarged side elevation of a detail; Fig. 6 is a longitudinal section of a portion of the machine showing 50 the crank by means of which it can be manually operated; Fig. 7 is an enlarged side elevation of the detail shown in Fig. 3; and Fig. 55 8 is a diagram illustrating the construction of the logarithmic scale.

Before proceeding to a more detailed ex-

planation of my invention, it should be understood that while the form of the machine as illustrated in the accompanying drawings is designed for use with the Briggsian system 60 of logarithms, in which the base is the number 10, the details of construction and the arrangement of certain of the parts, such as the scale, can be altered to adapt the machine to the use of other systems of logarithms, that 65 is, systems of logarithms having base values other than 10. In the following description and claims, the term "logarithm" as used is intended to apply to the Briggsian system of logarithms, which is one of the most widely 70 used.

Certain calculations, which are difficult and laborious to make when the ordinary rules of mathematics are applied, can be performed with ease and rapidity by the employment of logarithms. For example, the raising of a number to a power, or the extraction of any root of a number, are easily effected logarithmically, while they involve extended arithmetical calculations if carried 80 out in that way. By means of my calculating machine, such calculations are performed by means of logarithms and can be effected in a very simple manner and with great rapidity. At the same time, the device obviates the necessity of logarithmic tables, as by means of it the logarithm of any number, and conversely, any number corresponding to a known logarithm, can be obtained mechanically. In connection with the machine, 90 I employ a special form of logarithmic scale which is sub-divided into a number of sections and thus permits of the employment of an exceptionally great length of scale.

Each of the scale sections is in the form of 95 an arc of a circle, and all of the sections are so arranged on a scale-carrying band that each can be easily and quickly arranged in position to permit the calculations to be carried out. The diagram shown in Fig. 8 illustrates the method of laying out the logarithmic scale. The rectangle *a b c d* is bisected by the line *e f*. With the center *h* on the line *e f* an arc is described, passing through the points *a* and *b* and intersecting the line *e f* at *a k*. The length of this arc should be less than that of a full circle described with the radius *h k*. In the type of logarithmic scale which I employ in the form of the device shown, the arc *a b* is exactly equal in length 105 to one-third of the circumference of a circle described with the radius *h k*, and conse-

quently, the angle $a h b$ equals 120° . A further arc is described with the center on the line $e f$ passing through the points d , c , and intersecting the line $e f$ at i . The distance $k i$ is equal to $a b$, and $b c$; that is, the radius of the arc $d i c$ is equal to the radius of the arc $a k b$. The distance $k i$, is divided into a hundred equal parts, $k k'$, $k' k''$, $k'' k'''$, $k''' k''''$, $\dots$, $k^{98} k^{99}$. A series of arcs having the centers on the line $e f$, and intersecting the line $e f$ at the points k' , k'' , k''' , k'''' , $\dots$, k^{98} , and similar to the arcs $a k b$ and $d i c$ is described. Each of these arcs equals in length one-third of the circumference of a circle of similar radius.

In the practical form of the scale, the arcs are inscribed upon a band 1 of flexible material such as fabric or the like, and as is shown in Fig. 4. The scales 2 formed by the arcs 20 are designated successively, by indicating figures 3 arranged at one side of the band 1; these figures are 00, 01, 02, 03, 04 . . . 99. Each of the scale arcs 2 is divided in a thousand parts, that is, has a thousand graduations 4 inscribed thereon. The scale arcs indicate logarithmically, the numbers between 1.000 and 10.000. That is to say, the indicating figures 00, 01, 02, 03 . . . 99 of the scale arcs 2 represent the first two figures of 30 the mantissæ of the logarithms corresponding to the numbers from 1.000, (one) to 10.000, (ten) and as each of the arcs is divided into a thousand parts by graduations, the latter will run from 000 to 999 and will correspond 35 to the last three figures of the mantissæ of the logarithms of the numbers between 1.000 and 10.000. The latter, themselves, are inscribed upon the scale arcs at the graduations which indicate the logarithms corresponding 40 respectively to these numbers from 1.000 to 10.000. For example, the logarithm of the number 3.757 is 0.57484; consequently, the number 3.757 is indicated on the scale designated by the figure 57, that is, the 45 first two numbers of the mantissa .57484, and it is indicated at the four hundred and eighty-fourth graduation of the scale arc 57, reading from left to right, of the thousand graduations inscribed upon the scale arc. In 50 the illustration of the logarithmic scale employed, the scale arcs are not shown actually divided into a thousand parts but are provided with a smaller number of graduations, for the sake of convenience. Upon 55 the scale band at the side of the scale opposite to the indicating figures 3 are inscribed numbers 5, one for each scale, which correspond approximately, to the first number inscribed upon the respective scale. It will be 60 understood that the mantissæ of the logarithms of numbers which differ only in their decimal points, are the same, the characteristics alone changing. For example: The logarithm of 3.757 is 0.57484, and the loga-

rithm of 375.7 is 2.57484. Consequently, 65 while the scale arcs actually correspond to numbers from 1.000 to 10.000 they can be used for numbers from .0001 to 10.000 and by methods of approximation, for numbers above ten thousand. In general, the operation 70 of the scale may be exemplified as follows: If the logarithm of a number n comprises

$$a \text{ and } b \text{ the } \log. n = \frac{a}{100} + \frac{b}{100,000}.$$

The graduation for the number n is found 75 upon that arc which is designated at the side by the figure a , and at the b graduation, counting from left to right of the thousand graduations of the arc in question. For the sake of convenience I have chosen to employ 80 exactly one hundred scale arcs, and to divide each of the latter into a thousand equal parts. This relationship is not an arbitrary one and can be varied to suit convenience or individual preference. I prefer to employ 85 this number of arcs and this method of subdivision, as it permits a practical and efficient construction of the machine.

Referring more particularly to the drawings, 6 represents the base of the machine, 90 which, near the opposite sides, carries elongated walls or supports 7. A casing 8 is mounted upon the base and has a top or cover 9. Near the ends, the supports 7 have journaled therein shafts 10 and 11 which 95 carry rollers 12 and 13 respectively. The roller 12 has twenty-five teeth 14, at each end, adapted to engage with openings 15 at the opposite edges of the scale-band 1, the latter being rolled upon the roller 13 and passing over the roller 12. A shaft 16 is carried by the support 7 intermediate of the shafts 10 and 11, and has a roller 17 upon which a portion of the band 1 is rolled in the opposite direction to the rolling of the band upon the 100 roller 13. The band 1 extends from the roller 12 to the roller 13 adjacent to the under side of the cover 9, and can be moved with respect to the cover by operating the rollers, as will appear more clearly hereinafter. A pinion 18 is rigidly mounted upon the shaft 11 near one end thereof, and is in mesh with a gear-wheel 19 revolvably carried by one of the supports 7. The pinion has ten teeth, while the gear wheel has sixty teeth. The latter, further, has an arm 20 adapted to engage a stop 21 carried by the casing. The arrangement is such, that when the roller 13 is in its initial position the arm engages the stop and prevents further rotation of the roller 13 in one direction.

A crank 22 is rigidly carried by the shaft 10 and extends through a suitable opening of the casing. The crank has a spindle 23 projecting laterally therefrom and carrying a 121 revolvble handle 24 by means of which the crank can be manually operated. At the end, the handle has a plate 25 provided with

the adjacent gear 72 through a part of a revolution such that the drum 69 has been moved through one-tenth of a revolution. The drum 68 is slideable upon the shaft 67, 5 and by means of a handle 75 can be moved longitudinally of the shaft to disengage it from the intermediate wheel 73. By means of the handle 75 the drum 68 when disengaged from the intermediate wheel 73 can be 10 set into any desired position. The cover 76 of the counter has openings 77 through which the figures of the respective drums can be read, one at a time. Between the openings for the drum 68 and the remaining openings 15 is inscribed a decimal point 78.

At the side of the bracket 62 remote from the gear wheel 61 are revolubly carried pinions 79, each of which has twelve teeth, and which are in mesh. The bracket 62 is slideably carried upon the frame 63 and can be moved along a guideway 80 by means of a knob 81, to throw either the wheel 61 or the pinions 79 into mesh with the gear wheel 59 and the pinion 66. It will be understood 25 that when the gear wheel 61 is in an operative position the revolutions of the shaft 10 are indicated by the counter, each revolution being added to the revolutions already made. When the pinions 79 are in an operative position the action of the counter is reversed and each revolution of the shaft 10 is subtracted from the revolutions already indicated by the counter. The wheel 61 is held 30 against casual movement when the shaft 10 is revolving to return the scale-band to its initial position, by a spring 82 mounted upon the frame 63 and engaging the wheel 61.

At each end of the slot 32 is a recess 32^a which permits the appearance of the figures 40 at the opposite sides respectively of the scale band. By the use hereafter, of the term "to set" a number, is meant the bringing into the slot of that scale upon which the number in question appears and the placing of the 45 pointer with the sight 47^a over the graduation of the scale which corresponds to the number. The operation of the calculating machine is set forth in the following examples of the uses to which it can be put. In 50 each of the examples the machine is started from its initial position, that is, a position such that the hand 44 indicates 0, that the pointer is arranged at the left in its starting position and that ciphers appear in the sight 55 openings 77 of the counters. A stop 39^a on the cover 9 permits the operator to arrange the pointer exactly in its initial position.

Example I: What is $\log 371.5$?

In accordance with the logarithmic rule it 60 appears that the characteristic of the desired logarithm is 2. The number 371.5 is set and when this has been done the sight and pointer will lie above the graduation indicating the number 371.5. The scale arc upon which

the number 371.5 appears is characterized by 65 the figure 56 which appears in the recess 32^a at the left of the slot 32. In turning the scale band from its initial position to a position such that the scale arc 56 appears, the shaft 10 has actuated the counter so that the 70 figure 56 also appears to the right of the decimal point 78 in the corresponding sight opening 77. The number 56 represents the first two figures of the mantissa of the desired logarithm. The point 50 of the pointer 75 39 indicates the nine hundred and ninety-sixth graduation on the scale 53. The last number corresponds to the last three figures of the mantissa of the logarithm. Consequently, the $\log 371.5$ is 2.56996. It 80 will be understood that as the scale 53 in the form of the machine shown in the drawings is divided into a hundred points only, the last figure of the mantissa is approximated.

Example II: What is the number corresponding to the $\log 0.27883 - 2$?

The crank 22 is turned until the number 27 appears in the sight openings 77 to the left of the decimal point 78. The point 50 90 of the pointer is set at the graduation 883 of the scale 53. The sight 47^a of the pointer then indicates that the desired number is 19003. However, as the characteristic is minus 2, it appears according to the rule of 95 logarithms that the actual number is 0.019003.

Example III: $1.04^{10} = ?$

The number 1.04 is set. The number 0.01 then appears at the counter. The pointer is 100 set with the sight at the graduation 1.04 of the scale arc characterized by 01. The point 50 now indicates the graduation 703 on the scale 53. In raising a number to a higher power by means of logarithms, the logarithm 105 of the number is multiplied by the power to which the number is to be raised. Therefore, it is necessary to find the products of 01 $\times$ 10 and 703 $\times$ 10. These products are respectively 10 and 7030; the latter number 110 represents seven scale arcs and thirty parts of the eighth, as each scale is divided into one thousand parts. Consequently, the first part of the mantissa is to be increased by 7; that is, to 17, while the last three figures of 115 the mantissa are 030. The pointer is then set with the point 50 indicating 030 on the scale 53 and the crank is turned until the number 0.17 appears at the counter. The sight of the pointer then indicates the graduation 14801 of the scale arc characterized by 120 17, from which it appears that $1.04^{10} = 1.4801$.

Example IV: $\sqrt[3]{175.02} = ?$

The number 175.02 is set. The figures 24 appear at the counter. The pointer is arranged with the sight at the graduation 175.02 of the scale arc characterized by 24. The point of the pointer then indicates the

a rigid pin 26 arranged in a longitudinal bore of the spindle 23 and projecting toward the casing. At the outer end, the spindle 23 has a head 27 surrounded by a recess 28 of the handle. Within the recess 28, and engaging the head 27 is a helical spring 29 which normally forces the handle toward the crank and projects the end of the pin 26 beyond the same and into engagement with a plate 30. 5 having a series of recesses 31 arranged in a circle concentric with the axis of the crank. The arrangement of these recesses is such that when the pin 26 engages one of the recesses a scale arc is visible through a suitably formed slot or opening 32 in the cover of the machine. The shafts 11 and 16 have coiled springs 33 connected therewith and rigidly secured to one of the supports 7. The coiled springs tend to rotate the shafts 20 and to wind the scale band into an initial position, that is, the position such that the arm 20 engages the stop 21. If it is desired to set any particular scale in the slot 32, the handle 24 is pulled outwardly to free the pin 25 26 from the plate 30 and the crank is then turned until the desired scale arc appears in the slot. The handle is then released and the pin engages one of the recesses 31 of the plate to hold the band in position and prevent any movement of the rollers due to the springs 33.

The cover 9 of the machine casing has a circular opening 34 formed therein, in which is arranged a disk 35. The opening 34 includes the slot 32, one side of which is formed by the edge of the disk 35 as is shown most clearly in Fig. 2. The edge of the disk is serrated or is provided with teeth 36. The disk is revolvably mounted upon a cross-member 40 37 of the machine casing by means of a pivot pin 38. A swinging arm or pointer 39 is pivotally mounted upon the pin 38 and extends across the disk 35 and the slot 32. Above the pointer, the pin 38 has a rigid pinion 40 having ten teeth. The pinion 40 is in mesh with a gear wheel 41 having a hundred teeth and rigid with a spindle 42 arranged to revolve upon a support 43 projecting from the cross-member 37. An indicating hand 44 is 45 mounted upon the spindle 42 and extends over a graduated ring 45 mounted upon the cross-member 37. The ring 45 has inscribed thereon thirty graduations 46, running from 0 to + 15 and 0 to - 15.

55 The portion of the pointer 39 which extends over the slot 32 is formed into a bifurcated frame 47 upon the sides of which is mounted a slideable cross-bar 48 guided upon the sides by sockets 49. At the ends, the 60 sides join to form a point 50. Between the sides of the part 47 of the pointer, and aligned with the longitudinal center line of the pointer, is a sight 47^a by means of which the position of the pointer with respect to a 65 scale arc can be exactly determined. The

sight 47^a is in alignment with the point 50. The cross-bar sockets are serrated to engage at the periphery of the disk 35 and grip the same so that the disk is turned as the pointer is turned. A spring 51 secured to the cross-bar and the pointer, holds the former normally in engagement with the disk. The frame 47 has a button 52 by means of which the pointer can be manually operated. By moving the cross-bar against the tension of the spring, the sockets are released from the edge of the disk and the pointer can then be turned in one direction or the other without correspondingly actuating the disk. Concentric with the scale-arc slot 32, is a scale 53 inscribed upon the cover of the machine and having graduations from one to a thousand. In the drawings, the scale 53 is shown with only a hundred sub-divisions, for reasons of simplicity, but in the practical form of the device it is preferable to employ a scale with a thousand sub-divisions.

The disk 35 has three equi-distant indicating marks 54 thereon. The marks extend to the periphery of the disk and are arranged radially of the same, subtending angles of 120°.

At one side, the shaft 10 extends through a suitable opening of the casing wall and has a rigid laterally projecting arm 55 which carries a pivoted dog 56. A ratchet wheel 57 loose upon the shaft 10 and provided with twenty-five teeth is engaged by the dog 56. The latter is normally held in engagement with the ratchet wheel teeth by a spring 58. 95 A gear wheel 59 having twenty-five teeth, and rigidly connected with the gear wheel 57 by means of a sleeve 60, is in mesh with a second gear wheel 61 also having twenty-five teeth. The gear wheel 61 is revolvably mounted upon a bracket 62 slidably arranged upon a frame 63 carried at the side of the casing. A counter 64 has a shaft 65 passing therethrough and carrying a pinion 66 provided with ten teeth and normally in mesh with the gear wheel 61. A second shaft 67 is arranged in the counter and has three drums 68, 69, and 70 upon each of which are inscribed ten figures, from 0 to 9 inclusive. The drums 68, 69 and 70 are arranged in the order named from left to right. The drum 70 is operatively engaged by a wheel 71 having twenty teeth and rigid with the shaft 65. The drum 70 actuates the drum 69 through an intermediate gear 72. The drum 69 in turn actuates the drum 68 through an intermediate gear 73. The intermediate wheels 72 and 73 are mounted upon a suitable shaft 72^a carried by the counter frame. The arrangement is that of the ordinary counter and each of the drums 70 and 69 has a pair of teeth 74 which engages the adjacent intermediate wheel once during each revolution of each drum. Therefore, when the drum 70 has completed one revolution it has turned 120 125 130

graduation 308 of the scale 53. From this it appears that $\log 175.02 = 2.24308$.

In accordance with a rule of logarithms the $\log \sqrt[7]{175.02} = 1/7 \log 175.02$. Dividing 5 2.24 by 7 and 308 by 7 we obtain 0.32 and 044 respectively. Consequently,

$$\log \sqrt[7]{175.02} = 0.32044.$$

10 The crank is now turned until the number 0.32 appears at the counter. The pointer is set with the sight indicating the graduation 044 of the scale 53. When the pointer has been arranged in this position the sight indicates the number 20914 on the scale arc characterized by 32, and from this we find that

$$\sqrt[7]{175.02} = 2.0914.$$

Example V:

20 $1779 \times 0.19501 \times 288.05 \times 0.003803 = ?$

The characteristics of the individual factors are in the order named 3, -1, 2, -3. The summation of these characteristics—25 that is $3 - 1 + 2 - 3$ —yields as result 1. By means of the handle 75 the counter drum 68 is set independently of the other mechanism of the counter so that the figure 1 appears in the sight opening of the counter at the left 30 of the decimal point.

The number 1779 is set and the pointer is positioned with the sight indicating the graduation 1779 of the scale arc. The crank is then released to permit the scale arc band to return 35 to its initial position and thereupon the pointer is turned back into its original position, the cross-bar 48 being released so that the disk 35 is permitted to remain in the position to which it was brought when the pointer was 40 swung from the initial position to indicate the number 1779.

The number 19501 is set and the pointer positioned with the sight indicating the graduation corresponding to 19501 of the scale 45 arc. The scale arc band is then allowed to return to its initial position and the pointer is also returned to its initial position after being released from the disk. In the same manner the numbers 2885 and 3803 are successively set.

Each movement of the pointer from the initial position has rotated the disk to a certain extent. In setting the numbers successively, the scale arc band was unwound 55 and a certain number of the scale arcs, each of which corresponds to the first two figures of a logarithm, was registered in the counter. The number 2.58 now appears at the counter. By means of the button 81 and the movable 60 bracket 62, the pinions 79 are positioned between the gear wheel 59 and the pinion 66 so that the operation of the counter is reversed. That is, by means of the crank, the scale band is unwound from its initial position 65 and the counter is turned back until the

number 2.00 appears instead of 2.58. One of the indicating marks 54 of the disk 35 will be found to register with one of the graduations of the scale arc characterized by 58, visible in the slot 32, and the graduation in 70 question is found to be 38054. The figures 38054 constitute the resulting number, and as the characteristic 2 appears at the counter, the result of the calculation is 380.54.

As the disk is provided with equi-distant 75 indicating marks 54, one of the same will always be found at that portion of the disk which forms one side of the scale arc slot 32. As the counter is actuated only when the scale band is being wound in one direction, 80 the counter will add up automatically the numbers of the scale arcs which are successively set in the slot 32. For instance, if the scale arc band is first unwound from the initial position until the scale arc characterized by 85 30 appears, and then from its initial position until the scale arc characterized by 60 appears, the number .90 will appear at the counter. This means that the sum of the first two figures of the mantissæ of the logarithms indicated upon the respective arcs is .90, that is, .30 + .60.

Example VI:

$$\begin{array}{r} 9751 \\ \times 8.371 \times 50.55 \times 2.701 \\ \hline ? \end{array} \quad 95$$

The characteristics of the numerator is 3. The characteristic of the denominator factors are 0, 1, 0, and their sum is therefore 1. Consequently, the characteristic of the result is 2. By means of the handle 75 the counter is set so that the figure 2 appears at the left of the decimal point. The number 9751 is then set and the pointer positioned so that the sight indicates the graduation 100 9751 of the scale arc. The scale arc band is then permitted to return to its initial position and after releasing the pointer from the disk the pointer is turned back to its initial 105 position. By means of the button 81 the 110 counter is arranged so that its action is reversed; that is, instead of adding the successive movements of the scale arc band these are subtracted.

The number 8371 is then set and after releasing the pointer from the disk the pointer is moved from its initial position until it indicates the graduation 8371 of the scale arc. In other words, the pointer is set at the required number without turning the disk. 115 As soon as the pointer is set it is permitted to clamp against the disk periphery and is returned to its initial position, consequently carrying with it the disk.

The number 5055 is then set and the 120 pointer positioned in the same way at the graduation 5055 without rotating the disk. The pointer is then returned to its initial position, carrying with it the disk. In the same way the number 2701 is set and the 125

pointer moved from the graduation 2701 to its initial position, carrying with it the disk.

The number 0.93 now appears at the counter. An indicating mark 54 of the disk is found to correspond with a graduation 102 of the scale 53. The crank is then turned until the 0.00 appear at the counter, and it is then found that one of the indicating marks 54 of the disk corresponds with the number 10 8531 of the scale arc appearing in the slot 32. As the figure 0 appears to the left of the decimal place in the counter the result of the calculation is 8.531.

The pinion 40 and the gear wheel 41 are 15 so proportioned that every time the disk 35 makes a complete revolution the hand moves one-tenth of the distance around the graduated ring 46, that is, it moves over three graduations. Thus we find that each graduation 20 of the ring 46 corresponds to a third of a revolution of the disk 35, as the length of each scale arc is equal to one-third of the circumference of the disk, that is, the peripheral distance between any two of the indicating marks 54. Each time the disk 25 makes a third of a revolution the hand will move from one graduation to the succeeding graduation on the ring 46.

In the examples given above, the factors 30 and divisors were so chosen that the arcs, which, through the movement of the pointer and the disk are added, do not reach or exceed the length of a single arc. It often happens however, that the arc length is exceeded. When this occurs, the hand 44 indicates the total number of arc lengths through which the disk has been turned. For example, if during the course of a calculation the hand is positioned between +4 and +5 of 40 the graduated ring, it appears that the disk has been turned through four arc lengths. In this case, the last figure of the number appearing at the counter must be increased by four.

45 It will be understood that I do not wish to limit myself in the form of my calculating machine to the exact constructive details illustrated in the accompanying drawings. If so desired, the proportions of the operationally connected parts may be altered or varied and the method of operating the machine can also be changed. The underlying principles which I employ in this invention reside primarily in the form of the logarithmic scale, in the sub-division of the scale into a number of sections which permit the practical lengthening of the scale, in the provision of means for adding or subtracting the movements of the logarithmic scale-carrying 50 member, and in the provision of means for adding or subtracting numbers indicated by the scale arcs themselves.

Having thus described my invention, I claim as new and desire to secure by Letters 65 Patent:—

1. In a calculating machine, a logarithmic scale comprising a plurality of independent sections having successive graduations representing logarithmic values, and further having indicated thereon numbers corresponding to the logarithmic values. 70

2. In a calculating machine, a logarithmic scale comprising a plurality of independent sections each designated by a part of a logarithmic mantissa, and each having the remainder of the respective mantissæ indicated thereon by a graduation. 75

3. In a calculating machine, a logarithmic scale comprising a plurality of independent sections designated successively by the first 80 two figures of logarithmic mantissæ, and each graduated to indicate figures of logarithmic mantissæ other than the first two figures.

4. In a calculating machine, a logarithmic scale comprising a plurality of independent sections designated successively by the first 85 two figures of logarithmic mantissæ, and each having graduations indicating the numbers from 000 to 999, said scale having indicated thereon numbers corresponding to the logarithms represented by the section designations and graduations. 90

5. In a calculating machine, a logarithmic scale comprising independent sections each 95 designated by the first two figures of a logarithmic mantissa, each of said sections having one thousand graduations, whereby a number, the logarithm of which equals

$\frac{y}{100 + 100000}$ is found on the section designated 100 by x , and at the y -graduations of said x section.

6. In a calculating machine, a logarithmic scale comprising independent sections designated by the first two figures of different logarithmic mantissæ, each of said sections having one thousand graduations, and further having indicated thereon numbers corresponding to logarithms, whereby a number, 110 the logarithm of which equals $\frac{x}{100 + 100000}$ is indicated on the section designated by x and at the graduation of said x -section designated by y . 115

7. In a calculating machine, a logarithmic scale comprising separate sections arranged in arcs of similar circles, and having the centers in alinement.

8. In a calculating machine, a logarithmic scale comprising independent sections formed in the arcs of circles having substantially equal radii, the centers of said arcs being arranged in alinement, said arcs being designated respectively by parts of different logarithmic mantissæ, said arcs further being graduated to indicate figures other than said parts of the respective logarithmic mantissæ, and having inscribed thereon numbers corresponding to logarithms. 120 125 130

9. In a calculating machine, a movable logarithmic scale comprising separate sections, means for operating said scale, and a fixed scale adapted to coöperate with each 5 of said sections to permit the determination of points thereon. 70
10. In a calculating machine, a movable logarithmic scale comprising separate sections, means for operating said scale, means 10 for concealing all but one of said sections at a time, and a fixed scale adapted to coöperate with each of said sections to permit the determination of points thereon. 75
11. In a calculating machine, a movable 15 logarithmic scale comprising separate sections designated successively by the first two figures of logarithmic mantissæ, a fixed scale graduated to indicate figures of logarithmic mantissæ other than the first two 20 figures of the same, said fixed scale being adapted to coöperate with each of said sections to determine points on the same, said sections having indicated thereon numbers corresponding to the logarithmic values represented by the sections. 80
12. In a calculating machine, a movable logarithmic scale comprising separate sections, said sections being formed in the arcs of circles having the centers in alinement, 30 means for operating said scale, means for concealing said scale, whereby one of said sections appears at a time, a fixed scale concentric with said sections, and a pointer extending over said logarithmic scale and said 35 fixed scale and arranged radially with respect to said fixed scale and said logarithmic scale sections. 90
13. In a calculating machine, a movable logarithmic scale, means for actuating said 40 scale, and a counter for registering the movements of said scale. 95
14. In a calculating machine, a movable logarithmic scale comprising separate sections, means for actuating said scale, and a 45 counter for registering the sections through which said scale is moved. 100
15. In a calculating machine, a movable logarithmic scale comprising separate sections characterized successively by numbers 50 beginning with 00 and increasing one unit for each section, means for concealing said scale whereby but one of said sections appears at a time, means for actuating said scale, and a counter controlled by said actuating means and serving to register the sections successively appearing when said scale is actuated. 115
16. In a calculating machine, a movable logarithmic scale comprising separate sections characterized successively by numbers 55 representing the first two figures of logarithmic mantissæ, means for concealing said scale whereby but one of said sections appears at a time, means for actuating said scale, means for returning said scale to an initial position, and a counter controlled by said actuating means and serving to register the sections successively appearing when said scale is actuated. 120
17. In a calculating machine, a movable logarithmic scale comprising separate sections characterized successively by numbers representing the first two figures of logarithmic mantissæ, means for concealing said scale whereby but one of said sections appears at a time, means for actuating said scale, a counter controlled by said actuating means and serving for the addition of the corresponding numbers of sections successively appearing when said scale is actuated. 125
18. In a calculating machine, a traveling band having a logarithmic scale thereon, said scale comprising separate sections, means for actuating said band, and a counter for registering the number of scale sections through which said band is moved. 90
19. In a calculating machine, drums, a band arranged upon said drums, whereby said band travels when said drums are actuated, said band having a logarithmic scale thereon, said scale comprising separate sections, means for actuating said drums, means for normally returning said drums to an initial position, means for holding said band in a plurality of positions, and a counter for registering the number of scale sections through which said band is moved. 100
20. In a calculating machine, drums, a band arranged upon said drums and having a logarithmic scale thereon, said scale comprising separate sections, means for normally resisting the displacement of said drums from an initial position, means for limiting the movement of said drums, one of the limits of movement of said drums being their initial position, means for actuating said drums, means for holding said band in a plurality of positions, means for concealing said band whereby but one of said sections appears at a time, and a counter for registering the number of scale sections through 115 which said band is moved. 110
21. In a calculating machine, a logarithmic scale, a movable member adapted to coöperate with said scale, and a movable pointer extending over said scale and controlling said member. 120
22. In a calculating machine, a movable logarithmic scale, a movable member adapted to coöperate with said scale, a movable pointer extending over said scale and controlling said member, and means for registering the movements of said member. 125
23. In a calculating machine, a logarithmic scale, a second scale, a movable member having means for coöperating with said log- 130

- arithmic scale, and a pointer controlling said member and adapted to coöperate with both of said scales.
24. In a calculating machine, a logarithmic scale, a second scale, a movable member having means for coöperating with said logarithmic scale, a pointer extending over said scales and controlling said member, and means for registering the movements of said member.
25. In a calculating machine, a movable logarithmic scale, a fixed scale, a movable disk having means for coöperating with said logarithmic scale, a movable pointer extending over said scales and adapted to coöperate therewith, means for revolubly attaching said pointer to said disk, and means for registering the movements of said disk.
26. In a calculating machine, a movable logarithmic scale comprising separate successive sections formed in arcs of circles, means for concealing all but one of said sections at a time, a fixed scale concentric with the visible one of said sections, a movable disk concentric with the visible one of said sections, said disk having indicating means adapted to coöperate with said sections, a movable pointer extending over the visible one of said sections and said fixed scale and adapted to coöperate therewith, means for movably attaching said pointer to said disk whereby said disk can be caused to move with said pointer, and means for registering the movements of said disk.
27. In a calculating machine, in combination, a movable logarithmic scale, means for registering the movements of said scale, a movable member adapted to coöperate with said scale, means for registering the movements of said member, and a pointer extending over said scale and controlling said member.
28. In a calculating machine, in combination, a movable logarithmic scale, means for adding and means for subtracting the movements of said scale, a movable member
- adapted to coöperate with said scale, means for adding and subtracting the movements of said member, a fixed scale, a pointer extending over said scales and controlling said member.
29. In a calculating machine, in combination, a movable logarithmic scale, means for normally returning said scale to an initial position, means for holding said scale in a plurality of positions, means for adding and means for subtracting the successive movements of said scale, a fixed scale, a movable member adapted to coöperate with said scale, means for adding and means for subtracting the successive movements of said member, and a pointer controlling said member and adapted to coöperate with said scales.
30. In a calculating machine, in combination, a movable logarithmic scale comprising separate successive sections, each arranged in the arc of a circle, said sections being designated by the first two figures of logarithmic mantissæ, said sections being graduated to indicate figures of logarithmic mantissæ other than the first two figures, a fixed scale adapted to coöperate with said sections, means for actuating said logarithmic scale, means for adding and means for subtracting the successive movements of said logarithmic scale, a movable member adapted to coöperate with said logarithmic scale, means for adding and means for subtracting the successive movements of said member, means for limiting the movements of said logarithmic scale, and a pointer extending over said scales and having means for removably attaching to said member whereby said member is controlled by said pointer.
- In testimony whereof I have signed my name to this specification in the presence of two subscribing witnesses.
